UNITED STATES PATENT OFFICE

2,058,314

APPARATUS FOR USE IN THE MANUFACTURE OF LOOM REEDS AND LIKE ARTICLES

Arno Hornig, Pawtucket, R. I.

Original application November 22, 1933, Serial No. 699,207, now Patent No. 2,008,504, dated July 16, 1935. Divided and this application April 9, 1935, Serial No. 15,441

6 Claims. (Cl. 113—92)

My invention relates to improvements in loom reeds and an improved method of and an apparatus for their manufacture.

This application is a divisional application of my application for patent on Loom reed and method and apparatus for its manufacture, Serial Number 699,207, filed November 22, 1933.

A loom reed is preferably made up of a plurality of parallel flat wires or dents held by bars at spaced distances from each other. The ends of the dents have hitherto been mounted in two entirely different types of bars. They have either been mounted in so-called pitch bars, such as are shown in Patent No. 623,196, issued to Byron Wood on April 18, 1899, which comprise substantially semi-cylindrical wooden bars laid on each side of the dent ends reinforced inside by metal strips and having cord means wound around them in spiral formation in-between each dent and with the wooden bars, metal strips if employed and cord means covered over with a pitch covering to flexibly join the ends of said dents together at spaced distances, or the ends of the dents have been rigidly secured together by metallic means such as is shown in Patent No. 1,662,591, issued March 13, 1928 to Harry Titmas. A difficulty with the pitch bars alone has been that in due course of time the pitch and cord means become worn and the pitch bars tend to break up, or not hold the dents to the desired predetermined amounts apart. A disadvantage of the rigid metallic means rigidly securing said dents together has been that said means does not permit of any flexibility of the dents. Employing my invention, however, I am able to combine the advantages and largely eliminate the disadvantages of each of these former types. By providing a rigid fulcrum with my rigid attaching means inside of the usual pitch bar means I achieve a large degree of flexibility in the dents by permitting the dent ends to be mounted so that they may freely move laterally in the pitch bars and at the same time I strengthen the former types of pitch bar reeds by adding a rigid support inside the pitch bars thereof and I am enabled thereby to provide a reed which will stand up much longer than any pitch bar reed hitherto produced and which will have the usual advantages of a pitch bar reed. In order to solder a spiral spring to a pitch bar reed immediately inside of the pitch bars without melting the pitch bars, I have devised the novel method and apparatus shown and described herein for so doing. I have found in practice that this is an extremely difficult thing to do, namely, to apply the solder evenly to each side of the spring

to rigidly secure it to the dents without causing the heat of soldering to melt the pitch bars and I have accordingly devised an apparatus which when the reed is held in a vertical position will apply the solder to each side of the spring without causing any melting of the pitch bars.

Further features of my invention relate to the improved structural details of the improved apparatus I preferably employ for this purpose, which primarily adapted for applying solder to a reed bar may be employed if desired for applying solder along lines on both sides of other objects.

These and such other objects of my invention as may hereinafter appear will be best understood from a description of my improved reed and improved apparatus.

In the drawings, Fig. 1 is a disassembled side elevation of a reed after the pitch bars have been attached but prior to the attaching of the usual end cap members, springs and reinforcing spring strips and the soldering of the springs to the dent ends and showing the lower spring in the relative position it assumes in the completed reed.

Fig. 2 is a side elevation of a reed constructed in accordance with my invention.

Fig. 3 is a vertical sectional view thereof taken along the line 3—3 of Fig. 2.

Fig. 4 is an end view of the improved apparatus I preferably employ for simultaneously applying solder to each side of the spiral springs to secure them to the dent ends without melting the pitch bars.

Fig. 5 is a front elevation of the apparatus shown in Fig. 4.

In the drawings, wherein like characters of reference indicate like parts throughout, 10 generally indicates a reed constructed in accordance with my invention. As shown in Fig. 2, said reed 10 has a plurality of spaced flat wires or dents 15 vertically mounted in spaced side by side relationship and longitudinal pitch bars 12 flexibly joining opposite ends of said dents together preferably at points spaced from the ends 14 of said dents. While the pitch bars 12 may be constructed in any of the usual manners, such as shown in Patent No. 623,196 heretofore referred to, the pitch bars preferably include the preferably substantially hemi-cylindrical wooden strips 16 having the flat inner sides 18 adapted to abut the dents preferably at points equi-distantly spaced 20 from the ends thereof and arcuate outer sides 20. In my preferred embodiment, the outer sides of the wooden strips 16 are preferably provided with the longitudinal grooves 22 therein adapted to receive the reinforcing metal strips 24 which extend 25

longitudinally of said grooves substantially to the ends of the wooden strips. I then wind the cord means 26 spirally around said strips 16 and 24 with upper and lower winds 28 thereof extending 5 between the respective dents at the upper and lower portions of the pitch bars and I cover the outer surfaces of said bars and cord means with a covering of pitch 30 which may extend upwards and around the upper ends 14 of the dents 15. 10 Then if desired a paper covering 34 may be applied over said pitch bars 12 and upper ends 14 of said dents 15. The end cap members or bars 36 are preferably provided for joining the ends of the pitch bars 12 together and these are provided 15 with the preferably cylindrical caps 38 at each end thereof adapted to enclose the ends of the pitch bars, including said wooden strips 16 and metal strips 24 and be secured thereto by any suitable means, such as the nails 40 shown. As stated 20 hitherto, this is substantially the structure of the former type of pitch bar reeds.

The spiral spring 42 is then laid over the dents 15 immediately inside of said pitch bars 12 so as to have the winds 44 thereof interposed between 25 adjacent dents 15. This may be done by fitting the winds of the spring laterally from one side between said dents and not by screwing it in. In order to reinforce the metallic rigid fulcrum members in my device, I preferably employ the 30 metal strips 46 adapted to extend longitudinally within the outer segmental portions 48 of said spiral spring and over the end members 36. I then by means of the solder means 50 rigidly join the segmental strips 46 and spiral spring 42 to 35 each other and to the dents 15 and end members 36 on each side of said dents and end members to form rigid fulcrums for said dent ends inside said flexible pitch bars 12. It is thus obvious that the pitch bars form means for flexibly joining 40 the ends of said dents together and that the spring and solder, and reinforcing bars 46 where employed, form metal bars or means for rigidly securing said dents together at spaced distances inside of said flexible means.

45 Considerable difficulty was experienced in suitably soldering the outer surfaces of the metal springs 42 and metal strips 46 where employed to the dents 15 immediately inside of said pitch bars 12 without melting the pitch bars and in 50 order to accomplish this I have provided the improved type of apparatus shown in Figs. 4 and 5 for this purpose. Said apparatus includes the frame 52 suitably mounted on a support 54, although it is obvious that if desired the legs 56 of 55 said frame may be lengthened so that the frame 52 may be readily mounted on the floor. I provide suitable means to clamp said reed constructed as aforesaid to said frame 52 in a vertical position, in my preferred embodiment, said means includes 60 the vertical forwardly extending arms 58 longitudinally adjustable in slots 60 in said frame and secured thereto by the bolt and nut means 62 in adjustable positions thereon. I provide the clamps 64 each having a vertical slot 66 on one 65 end thereof to receive the upstanding end 68 of an arm 58 therein and be vertically adjustably secured thereto by means of the set screw 70. The front end of said clamp 64 is provided at its lower surface with the longitudinal slot 72 for receiving the dent end rib 39 of said pitch bar. A suitable vertically adjustable support 73 is provided 70 preferably extending the length of the frame and having a longitudinal groove 74 therein for receiving the lower dent end portion 39. Said 75 supporting means 73 is preferably provided with

the depending end legs 77 having the vertical slots 78 therein so that it may be vertically adjustably secured to the frame ends by the locking bolts 80.

I provide the solder troughs 82 extending longitudinally of said frame adapted to hold the solder 84 and I provide suitable means such as the gas burners 86 for heating said solder troughs, although it is obvious that any suitable type of heating means may be employed. I 10 also provide cooper bars 88 extending longitudinally of said frame and suitable means to raise said cooper bars 88 from said solder troughs 82 to about opposite side portions of said lower spiral spring 42 simultaneously with equal pressure to apply the solder retained in said cooper bars 88 with equal pressure to opposite sides of said spiral spring simultaneously. While any suitable means may be provided for this purpose, in my preferred embodiment, said means includes the shafts 90 extending through said frame, each having a gear 92 of equal size intermeshing with the respective opposite shaft gear 92 on each end of each shaft exterior of the frame. The handle 94 is provided to oscillate one of said shafts 90 to cause an equal movement of each of said shafts 90 through the medium of the intermeshing gears 92. The supporting bars 96 are provided projecting radially upwardly from each end of each shaft 90 having the outer ends bent first laterally as at 98 and then upwardly as at 100 for mounting of the cooper bars 88 thereon. The spring abutting portions of the cooper bars may if desired, be provided with solder grooves 102 to receive the solder from the solder baths 84 and bring it upwards to be applied against the outer surfaces of the spiral spring 42. If desired, as shown, the cooper bars 88 in addition to being supplied with the arcuate solder grooves 102 may be provided with the solder catching steps 104.

It is thus obvious that the formed reed 10 may be clamped to the frame 52 by means of the clamping means 64 and support 73, with the handle 94 first rotated to a position to receive the cooper bars 88 within the solder tanks 82 and that on rotation thereof each cooper bar will be raised equal amounts with equal pressure to about opposite sides of said spiral spring 42 to apply solder with equal pressure thereto at aligned points thereon. It is thus obvious that by employing this improved apparatus, I am enabled to apply even amounts of solder on each side of the longitudinally extending spiral spring to secure said spiral spring to said dents without melting the adjacent pitch bar, by applying the solder through the medium of the cooper bars along the spiral spring only.

It is thus apparent that I have provided a novel type of apparatus capable of producing the novel type of reed having the advantages described above.

It is understood that my invention is not limited to the specific embodiments shown and methods described and that various deviations may be made therefrom without departing from the spirit and scope of the appended claims.

What I claim is:

1. In an apparatus for evenly supplying solder along lines on opposite sides of an object, a frame, means to clamp said object to said frame in a vertical position, solder troughs mounted on said frame and extending along each side of said object, shafts extending through said frame, aligned equal sized intermeshing gears

mounted on the ends of said shafts, a handle to rotate one of said gears to cause an equal movement of each of said gears and shafts, means to heat said solder troughs, supporting bars projecting radially outwardly and upwardly from each end of said shafts having outer ends bent first downwardly and then upwardly and staggered in respect to opposite bars and cooper bars each extending substantially the 10 length of said object and having an arcuate solder groove on the inner edge thereof secured to the ends of said supporting bars movable from positions within said solder troughs to positions causing the solder grooves thereof to abut predetermined opposite aligned surfaces of said object on rotation of said handle.

2. In an apparatus for evenly supplying solder on opposite sides of a reed, a frame, means to clamp said reed to said frame in a vertical position, solder troughs mounted on said frame and extending along each side of said reed, shafts extending through said frame, aligned pairs of equal sized intermeshing gears mounted on each end of said frame on the ends of said shafts, a handle 25 to rotate one of said gears to cause an equal movement of each of said gears and shafts, means to heat said solder troughs, supporting bars projecting radially outwardly and then upwardly and staggered in respect to opposite bars and cooper bars extending substantially the length of 30 said reed and having an arcuate solder groove on the inner edge thereof secured to the ends of said supporting bars movable from positions within said solder troughs to positions causing the solder grooves thereof to abut predetermined opposite aligned surfaces of said reed on rotation of said handle.

3. In an apparatus for supplying solder on opposite sides of an object, a frame, means to clamp 40 said object to said frame, solder troughs mounted on said frame on each side of said object, shafts mounted on said frame, equal sized intermeshing gears mounted on said shafts, means to rotate one of said gears to cause an equal movement 45 of each of said gears and shafts, means to heat

said solder troughs, supporting bars projecting radially outwardly and upwardly from said shafts having outer ends bent first downwardly and then upwardly and cooper bars secured to the ends of said supporting bars movable from positions within said solder troughs to positions causing the ends thereof to abut opposite surfaces of said object on rotation of said shafts.

4. In an apparatus for supplying solder on opposite sides of a reed, a frame, means to clamp 10 said reed to said frame, solder troughs mounted on said frame on each side of said reed, shafts mounted on said frame, equal sized intermeshing gears mounted on said shafts, means to rotate one of said gears to cause an equal movement of 15 each of said gears and shafts, means to heat said solder troughs, supporting bars projecting radially outwardly and upwardly from said shafts having outer ends bent first downwardly and then upwardly and cooper bars secured to the ends of 20 said supporting bars movable from positions within said solder troughs to positions causing the ends to abut predetermined opposite surfaces of said reed on rotation of said shafts.

5. In a soldering apparatus, a frame, means to 25 immovably support an object on said frame, solder trough means mounted on said frame on each side of said object, two cooper bar means, means to movably mount each cooper bar means on said frame on opposite sides of said object and 30 means to move said mounting means and cooper bar means equal amounts from said solder trough means to abut opposite sides of said object with equal pressure to apply solder only along opposite lines on said object.

6. In a soldering apparatus, a frame, means to rigidly support an object on said frame, solder trough means mounted on said frame, cooper bar means, means to movably mount each cooper bar means on said frame and means to move said 40 mounting means and cooper bar means from said solder troughs to abut opposite sides of said object with equal pressure to apply solder only along opposite lines on said object.

ARNO HORNIG. 45
